Chicago, Ill., a corporation of Indiana

Application October 15, 1940, Serial No. 361,270

3 Claims. (Cl. 196—48)

This invention relates to certain new and useful improvements in the conversion of low antiknock hydrocarbon fractions to useful products such as high antiknock motor fuels and high antiknock aviation fuel. The invention has in view the provision of a combination process in which the low antiknock components of virgin petroleum naphthas are treated in an integrated process which is highly efficient in attaining the ultimate object of maximum yield of high antiknock naphthas.

Virgin naphthas of motor fuel distillation range contain variable proportions of straight-chain paraffin hydrocarbons and naphthenic hydrocarbons with minor proportions of aromatic hydrocarbons. For example, virgin naphthas from Pennsylvania crudes and Michigan crudes may contain as high as eighty to ninety per cent paraffins, the major part of which are straight-chain paraffins and as low as five to fifteen per cent of naphthenic hydrocarbons. On the other hand, naphthas from Mid-Continent crude and from California crude contain as high as twenty per cent to thirty-five per cent of naphthenic hydrocarbons and from fifty to seventy per cent of paraffin hydrocarbons. Since the straight-chain paraffin hydrocarbons and the naphthenic hydrocarbons are of low antiknock value it is highly desirable to convert the former to branched chain paraffin hydrocarbons and the latter to aromatic hydrocarbons boiling within the gasoline boiling range in order to obtain maximum yields of high antiknock value naphthas.

It is an object of this invention to provide an improved process for converting the straight-chain paraffins in a paraffinic naphtha which also contains naphthenes and aromatics, to isobutane. Another object of this invention is to convert the straight-chain paraffin hydrocarbons of such a naphtha to condensable olefins. Still another object of this invention is to react the isobutane and the condensable olefins obtained from the straight-chain paraffins to form high antiknock branched chain paraffinic naphthas which distill in the aviation gasoline boiling range. A further object of this invention is to raise the antiknock properties of a low antiknock naphtha by removing therefrom, in a catalytic conversion process, a substantial part of the low antiknock straight-chain paraffin hydrocarbons. Another object of this invention is to convert the low naphthenic hydrocarbon components of a paraffinic naphtha to high antiknock aromatics. A still further object of this invention is to provide a continuous process in which the catalysts employed may be utilized effectively for the production of high antiknock motor fuels until spent and then regenerated without interruption of the continuous process. Further objects will become apparent as the description of the invention proceeds, read in conjunction with

the accompanying drawing which is a diagrammatic representation of an apparatus for carrying out our invention.

We have found that straight-chain paraffinic naphthas can be catalytically converted to a gaseous product which is largely isobutane by passing the naphtha over a gel catalyst of the alumina activated silica type at low space velocities of the order of 0.01 to 1.0 volume of liquid 10 per volume of gross catalyst space per hour and at temperatures within the range of 575° F. to 850° F. This conversion process is carried out at absolute pressures within the range of fifteen pounds and sixty-five pounds per square inch. Moreover, we have found that by operating in the upper part of the above temperature range, say 800° F. to 850° F., the gaseous product consists primarily of isobutane and condensable olefins in such proportion that the gaseous mixture may be alkylated to produce branched chain paraffinic hydrocarbons boiling within the gasoline range. We have also found that if a paraffinic naphtha is passed over a solid catalyst comprising a mixture of a cracking type catalyst, such as alumina activated silica and a dehydrogenation type catalyst, such as metallic oxide activated alumina, at 15 temperatures within the range of 750° F. to 900° F., at space velocities within the range of 0.01 and 1.0 volume of liquid feed per volume of gross catalyst space per hour and at absolute pressures within the range of ten pounds and sixty pounds per square inch, relatively large volumes of condensable olefins are produced. Under these operating conditions, any naphthenes present in the 20 feed to such a catalyst bed are also dehydrogenated to high antiknock aromatic hydrocarbons.

In practicing the invention, we prefer to fractionate at least a major part of the naphtha feed 25 stock in order that we may convert the paraffin hydrocarbons of less than seven carbon atoms directly to the branched chain paraffins. This lower boiling fraction of the naphtha feed stock will contain only limited amounts of aromatic hydrocarbons and hence we are able to isomerize it to branched chain paraffin hydrocarbons over aluminum halide type catalyst. Aromatic hydrocarbons tend to deteriorate the aluminum halide catalyst. Thus we reserve the C₇ and higher 30 fraction of the feed, which contains aromatics and naphthenes in addition to paraffins, for conversion over the alumina activated silica gel cracking catalyst and/or for conversion over the mixed alumina activated silica gel catalyst and metallic oxide activated alumina catalyst. The isomerized C₆ and C₅ hydrocarbons are blended 35 with the alkylated isobutane and utilized as aviation fuel or the blend may be added to the converted naphtha to produce high antiknock motor fuel. The C₄ and lighter fraction of the virgin 40

naphtha feed passes to the alkylation step which is described below.

Briefly, the invention as illustrated by the accompanying drawing, contemplates the fractionation of a virgin naphtha containing straight-chain paraffins, naphthenes and aromatics boiling within the range of 60° F. to 400° F. into a C₄ and lighter fraction, a C₅+C₆ fraction and a C₇ and higher fraction. The C₇ and higher fraction is heated to a temperature within the range of 575° F. to 850° F., preferably 750° F. to 800° F., and is then passed over a catalyst bed in a conversion zone which may be designated as a cracking zone in which the catalyst comprises an alumina activated silica gel. The product from this conversion step is fractionated into an overhead gaseous fraction which is extremely high in isobutane content. The major part of the liquid fraction is recycled to the heating step and thence to the said cracking zone to convert more of the straight-chain paraffins to isobutane. A part of the liquid fraction is returned to the furnace and reheated in a separate coil to a higher temperature, for example, 750° F. to 900° F., but preferably from 850° F. to 900° F., and then passed to a conversion zone containing a mixture of a cracking catalyst and a dehydrogenation catalyst such as alumina activated silica mixed with a metallic oxide activated alumina catalyst. We have found that chromium oxide activated alumina is a suitable dehydrogenation catalyst for mixing with the alumina-silica catalyst in this conversion zone which may be designated as a dehydrogenation zone. The product from this conversion step is fractionated and the high antiknock value liquid fraction from which a major part of the paraffins have been removed, either by cracking to isobutane in the cracking zone or to condensable olefins in the dehydrogenation zone and in which the naphthenes have been converted to aromatics, is withdrawn for blending. If desired the C₇ and higher fraction may be sent to the dehydrogenation zone and a part of the liquid fraction from the fractionation of the dehydrogenation product may be recycled to the cracking zone, in which case the products from the two conversion zones may be fractionated in a common fractionator, thus eliminating the necessity of a separate fractionation of the catalytically cracked product. The isobutane plus normal butane overhead product from the fractionation of the product of the cracking step is alkylated with the condensable olefins from the fractionation of the product of the dehydrogenation step by intimately contacting the liquefied mixture with sulfuric acid of 95% to 103% concentration at temperatures within the range of 30° to 150° F. for periods of from five minutes to sixty minutes and at pressures sufficient to keep the reactants in the liquid phase. The ratio of isobutane to condensable olefins should be at least 2 mols of isobutane for one mol of olefins. The alkylated product is separated from the unreacted gases by fractionation and used as a high antiknock value blending naphtha for aviation gasoline or it may be blended with the high antiknock value naphtha from the cracking and dehydrogenation steps. Unreacted normal butane is passed to a catalytic isomerization step to produce additional isobutane for the alkylation reaction.

The C₅+C₆ fraction from the virgin naphtha feed is isomerized along with the recycle normal butane from the alkylation reaction to produce simultaneously isobutane and branched

chain C₅ and C₆ paraffin hydrocarbons by intimately contacting this fraction and the normal butane with aluminum halide or aluminum halide-hydrocarbon complex catalyst, preferably aluminum chloride or aluminum chloride hydrocarbon complex, at temperatures within the range of 250° F. to 400° F. The amount of catalyst used may be from five to fifty per cent of the weight of the hydrocarbon feed. The catalyst is activated by the addition of hydrogen chloride to the reactor to the extent of from five-tenths to five per cent of the weight of the hydrocarbon feed. The isomerization reaction is carried out in the presence of hydrogen or a gas containing hydrogen. We prefer to use at least a part of the hydrogen and methane containing gas from the dehydrogenation step for this purpose. Pressures in the isomerization step may be within the range of 200 to 3000 pounds per square inch. The product from the isomerization step is passed to the dehydrogenation product fractionating step from which the isomerized C₅+C₆ cut is withdrawn as a high antiknock blending naphtha, isobutane being separately recycled to the alkylation step.

In converting low antiknock value naphthas, which contain very low percentages of naphthenes, to high antiknock blending naphthas by our process it is sometimes unnecessary to utilize the dehydrogenation step in which the feed is contacted with the mixed cracking and dehydrogenation catalysts. We have found (see Table I below) that when operating the cracking reactor at a temperature of 823° F. the gaseous product contains a weight ratio of isobutane to total gaseous olefins reactive in a sulfuric acid alkylation process of approximately 29.0 to 27.6, which corresponds to a mol ratio of approximately 22.0 to 25.6. Keeping in mind that one mol of olefin reacts with one mol of isobutane in the alkylation reaction, it is readily seen that by isomerizing the normal butane produced in the cracking reactor and also the butane in the overhead fraction of the fresh feed it is possible to maintain a properly proportioned feed to the alkylation reaction without using the dehydrogenation reactor to produce olefins. Any deficiency in hydrogen for pressuring the isomerization reaction may be furnished from an outside source for this type of operation. The final products from this type of operation are the same as from the process when both the cracking and dehydrogenation reactors are used except that the product contains a lower percentage of aromatic hydrocarbons. This type of operation may also be used when it becomes necessary to regenerate the catalyst in the dehydrogenation reactor.

In a third embodiment of the invention the dehydrogenation reactor may be operated without the cooperation of the cracking reactor. Referring to Table II we have found that if a paraffin hydrocarbon fraction is passed over a mixed catalyst comprising an alumina activated silica gel and a chromium oxide activated alumina catalyst at 893° F. no isobutane and very little normal butane is formed but the major part of the gaseous product consists of condensable olefins which may be polymerized by either the cold sulfuric acid process or the hot sulfuric acid process. The polymerization process can be carried out in the alkylation reactor and the spent alkylation sulfuric acid catalyst can be reduced in concentration to a concentration within the range of 60% to 80% acid and used for this step. The polymerized product can be fractionated to eliminate polymers boiling above the gasoline distillation range and the polymer of suitable distillation range can be hydrogenated to aviation motor fuel or it can be added directly to the liquid product from the dehydrogenation step to raise the average antiknock value of such stock. The polymerization by the hot acid method is carried out at temperatures within the range from about 160° F. to 200° F. at atmospheric pressure with contact time within the range of from thirty seconds to three hundred seconds. This type of operation is desirable when the feed stock consists of a naphtha containing a relatively low percentage of paraffins and a high percentage of naphthenes. This type of operation may also be utilized during those periods when it becomes necessary to regenerate the catalyst in the cracking reactor. During operation according to this method the isomerizer may be used to isomerize only the C₅+C₆ fraction of the fresh feed.

Other embodiments of our invention, such as passing fresh feed to the cracking reactor and to the dehydrogenation reactor in parallel with separate fractionation of the product and separate recycle to the respective reactors or with fractionation in a common zone and consequent recycle of mixed liquids to either or both reactors or a combination of any of the methods of operation described above are contemplated by this invention. For the purpose of illustrating the invention operation with a feed stock such as a Mid-Continent naphtha containing straight-chain paraffins, aromatics and naphthenes is described below.

Referring now to the drawing, which is a simplified flow diagram illustrating one embodiment of our invention, a virgin naphtha boiling within the range from about 60° F. to about 400° F. is 75

passed via line 10 by pump 11 through valved lines 12 and 15 to fractionator 16 and furnace feed line 21 respectively, the streams being proportioned by adjustment of valves 13 and 14. 5 We prefer to pass at least seventy per cent of the fresh feed through fractionator 16 in order to separate the major part of the lower boiling fraction of the feed which may be isomerized directly to high antiknock value light naphtha suitable for blending in aviation gasoline. Fractionator 16 is provided with reflux means 17 and reboiler means 18. A side stream in line 133 containing primarily pentanes and hexanes is withdrawn from fractionator 16 by pump 134 as feed stock for the isomerization step which is described in more detail below. The C₄ and lighter overhead fraction from fractionator 16 is passed by valved line 96 to alkylator 105 which is also described below. 10 The C₇ and higher fraction of the naphtha is passed by means of pump 20 in line 19 to valved line 21 where it is mixed with non-fractionated virgin naphtha feed and the mixture is passed through valve 23 in line 22 which leads to heating coil 25 in furnace 24, valve 90 in line 89 being closed. The naphtha is heated in coil 25 to a temperature within the range of 575° F. to 850° F., preferably 750° F. to 800° F., within which temperature range it is passed via transfer line 26 and valve 27 to catalyst chamber 28 which is filled with a refractive gel catalyst of the alumina activated silica type. This catalyst may be prepared by immersing commercial silica gel in an aqueous solution of an aluminum salt, 25 draining off the supernatant solution, washing the gel, and drying and heating the product for several hours at temperatures of from 800° F. to 1100° F. The finished catalyst contains from 95% to 99.5% silica gel activated with from 0.5% 30 to 5% alumina. We may also employ an alumina-activated silica gel catalyst prepared by cogelling an alumina sol with a silica sol in such proportion as to produce a cogel comprising from about one to twenty parts by weight of alumina and from about 80 to 99 parts by weight of silica in the dried gel product. Other refractory type cracking catalysts such as acid treated clay and silica gel activated with such metallic oxides as magnesium oxide and boron oxide may 35 also be used in cracking chamber 28. The space velocity in catalyst chamber 28 which is operated at absolute pressures within the range of 15 pounds per square inch and 65 pounds per square inch, is within the range of 0.01 and 1.0 volume 40 of liquid feed per volume of apparent catalyst space per hour based on the paraffin hydrocarbon content of the feed. We prefer to operate at space velocities within the range of 0.04 and 0.1 volume of paraffin hydrocarbons per volume of catalyst per hour or at such a space velocity that from about 5% to about 15% of the straight-chain paraffin hydrocarbons in said naphtha are converted per pass through the reaction zone. 45 The product from catalyst chamber 28 is withdrawn through valved line 29 and it is passed via valve 30 in line 29 and valve 31 to cooler 32 in line 34 where it is partially condensed. The condensed product is transferred, by pump 33 in line 34 to hydrogen release drum 35 whence non-condensed gases are released through valve 36 in line 37 to isomerization feed line 67 and the liquid product is passed from drum 35 via line 38, pump 39 and line 40 to fractionator 41. Since hydrogen and non-condensable hydrocarbons constitute a very small percentage of the 50

product from reaction chamber 28 the product may be passed directly to fractionator 41 via valved lines 42 and 43 with valve 44 open and valve 45 closed. Fractionator 41 with reflux producing means 46 and reboiler 47 serves to separate the C₄ and lighter hydrocarbons which contain a large percentage of isobutane from the liquid product. The butanes pass via valve 94 in line 95 and line 77 to the alkylator feed line 98. The liquid product is withdrawn from fractionator 41 through side drawoff line 48. Hydrocarbons boiling above normal motor fuel boiling range may be drawn off through bottom drawoff 48a. By proper adjustment of valve 50 in line 49 which joins line 48, valve 51 in line 52, valve 54 in recycle line 55 and valve 56 in finished product line 57, the liquid product from fractionator 41 may be sent in part to coil 91 in furnace 24 through lines 49 and 85 and thence by line 92 to dehydrogenation reactor 58, and the major part of the product may be recycled by means of pump 53 through lines 52 and 55 to coil 25 in furnace 24 and thence to reaction chamber 28 for the production of additional isobutane. We prefer to operate with valve 56 in line 57 closed when processing a virgin naphtha containing appreciable amounts of naphthenes in order that these be converted to aromatics in reactor 58 before blending the liquid product to form high antiknock gasoline.

Referring to Table I above, a conversion per pass of approximately eleven per cent by weight of the paraffin hydrocarbons may be expected in reactor 28 when operating within the range of 750° F. to 800° F. In order to convert a major part of the paraffin hydrocarbon components of the feed in reactor 28 we maintain a recycle ratio of from about eight to about twenty parts by weight of recycle to one part by weight of virgin feed. When processing feed stocks containing a relatively high percentage of paraffin hydrocarbons the recycle ratio will be in the upper part of the above range while a feed stock containing a relatively low percentage of paraffin hydrocarbons will not necessitate such high recycle ratios.

In order to more completely reduce the paraffin hydrocarbon content of the product in side drawoff line 48 and thereby produce condensable olefins and also to dehydrogenate the naphthenes therein contained to aromatics, valve 50 is partially opened and the stream is directed to furnace coil 91 in furnace 24 via lines 85 and 89 by means of pump 53. This stream is heated to a temperature within the range from about 750° F. to about 950° F., preferably 825° F. to 900° F., and passes by line 92 to catalytic reaction chamber 58 which is filled with a mixed catalyst comprising from about 1 to 10 parts by weight of alumina activated silica gel catalyst intimately mixed with from about 99 to 90 parts by weight of a metal oxide-activated alumina catalyst such as an "activated alumina" supported chromium oxide catalyst. We prefer to use in reactor 58 a catalyst comprising alumina impregnated with 5 to 20 parts by weight of chromic oxide, preferably 10 parts by weight of chromic oxide, mixed with a second catalyst prepared by absrptolytically depositing Al₂O₃ on SiO₂ gel as described above. The chromic oxide-activated alumina catalyst may be prepared by immersing commercially "activated alumina" in an aqueous solution containing the desired amount of chromic oxide in the form of the acid or suitable salt, evaporating off the water, drying

the product and heating the same at 1200° F. for one hour. The powder is then pelleted to the desired particle size. Other metallic oxides, such as molybdenum oxide and vanadium oxide may also be used to activate the alumina by using the appropriate water soluble acid and/or water soluble salt. The space velocity in reactor 58 may be within the range of 0.01 to 1.0 volume of paraffin hydrocarbons (liquid) per gross volume of catalyst per hour. The operating pressure (absolute) in reactor 58 is within the range of from 10 pounds to 65 pounds per square inch. In reactor 58 the major part of the remaining paraffin hydrocarbon components of the naphtha are dehydrogenated and cracked to a gaseous product, a high weight per cent of which product consists of condensable olefins suitable for feed to the alkylation step which is described below. We have found (Table II above) that a conversion of 14 per cent per pass of paraffin hydrocarbons over the above mixed catalyst may be obtained at a temperature of 893° F., at space velocity of 0.06 volume of liquid feed per volume of catalyst space per hour and atmospheric pressure and hence, in order to reduce the paraffinic content of the residue naphtha to a minimum, we prefer to operate at a recycle ratio of from about five to twelve parts by weight of naphtha bottoms from the fractionation of the product from reactor 58 (fractionator 72) to one part by weight of feed to reactor 58 from line 49. The naphthenes of the naphtha are converted to aromatics in reactor 58 thus further increasing the antiknock value of the residual naphtha.

35 The product from reactor 58 passes via line 59, valve 60, cooler 61, compressor 62 and line 63 to hydrogen release drum 64 where hydrogen and non-condensable gases, such as methane, ethylene and ethane are separated and pass via lines 65 and 67 to the isomerization reactor 137. These may be passed in part to the fuel burning line through valved line 68 which joins line 65 by adjusting valve 66 in line 65 and the valve in line 68, or any excess of these gases not required in isomerization reactor 137, when reactor 58 is on stream in the reaction part of the cycle, may be passed to storage for use in reactor 137 when the catalyst in reactor 58 is being regenerated. Still another use for this hydrogen is for the hydrogenation of polymer produced when alkylator 105 is being used as a polymerizer, which operation is discussed below. Also, the hydrogen may be used to suppress carbon formation in reactor 58. Condensate from drum 64 to which product from line 63 is introduced at pressures within the range of 300 pounds to 400 pounds per square inch, passes by line 70 and pump 71 to fractionator 72 which is provided with reboiler 73 and reflux means 74. Residual non-condensable gases pass overhead via valved line 75 to the fuel burning line. A side stream, predominantly C₃ and C₄ hydrocarbons, is withdrawn from fractionator 72 through line 76 and passes via line 77 to alkylator hydrocarbon feed line 98. This stream in line 76, which consists in large part of condensable olefins, may be directed through line 78 when alkylator 105 is being used as a polymerization reaction chamber. Fractionator 72 is also used to separate the liquid isomerizer reaction products which are introduced to fractionator via line 155 and hence a C₅+C₆ side stream is trapped out of fractionator 72 which is passed via lines 79 and 130 by pump 80 to product line 57 for blending with the aromatic bottom product from fractionator 72 or

75

this C₅+C₆ stream may be passed via lines 79 and 79a to an aviation gasoline blending tank (not shown). The aromatic naphtha bottoms are withdrawn from fractionator 72 via line 81 and pump 82, a major part of this stream being recycled to coil 81 in furnace 24 via line 85, the remainder being eliminated as high antiknock naphtha via line 57. Any hydrocarbons boiling above normal motor fuel boiling range may be withdrawn through bottom drawoff 81a.

As stated above, we may operate our process using a common tower to fractionate the products from the catalytic cracking step and the catalytic dehydrogenation step. By properly adjusting valve 23 in line 22 and opening valve 90 in line 89 the C₇ and higher fraction may be passed via heating coil 91, line 92 and valve 93 to dehydrogenator 58 for the initial conversion step in which condensable olefins and hydrogen are produced. The product is flashed in release drum 64 and fractionated in fractionator 72 and the major part of the liquid bottom fraction may be recycled via line 81, pump 82, line 85 and line 86 to coil 25 via line 26 and thence to reactor 28 where isobutane is produced in the cracking operation. The product from reactor 28 is withdrawn via line 28 and passes to the dehydrogenator product line 59. By adjusting valve 84 in line 81, valves 83 and 88 in line 85 and valve 87 in line 86, the liquid fraction from fractionator 72 may be proportioned into finished high antiknock fraction drawoff, recycle feed to the dehydrogenation step and recycle feed to the catalytic cracking step as desired. Virgin C₇ and higher naphtha may be passed in parallel to reactors 28 and 58 by partially opening valve 23 in line 22. The chief advantage of passing the major portion of the virgin feed to the dehydrogenation step with operation of the catalytic cracking reactor primarily on recycle from the dehydrogenation step is possible heat economy without sacrifice of the desirable dehydrogenation of naphthenes to aromatics. This type of operation is desirable when the virgin feed stock is high in naphthenic hydrocarbon content. When the virgin feed stock is highly paraffinic with very low naphthenic hydrocarbons present in the feed, reactor 28 may be operated at higher temperatures, say 800° F. to 850° F., and the product may be fractionated either in fractionator 41 or 72 as described above.

Referring now to the alkylation step of our process, the butane overhead stream from fractionator 16 passes via line 98 and valve 97 as alkylator feed stream to line 98 where it is mixed with the isobutane rich gaseous stream from line 77 which connects with fractionator 41 overhead discharge line 95. Isobutane may be introduced to line 98 from an external source through valve line 99. Condensable olefins pass via fractionator 72 drawoff line 78 to line 77 and thence to line 98 or these olefins may be added directly to the acid catalyst valved line 106 through line 78. Condensable olefins from an external source may be added either directly to the acid catalyst by means of lines 100 and 101 or the olefins may be passed through lines 100 and 102 to line 77. The mixed butane and olefin stream is compressed by compressor 103 and passes by line 104 to alkylation reactor 105 where the mixture is intimately contacted with sulfuric acid of 95% to 103% strength which is introduced to line 104 via line 106 and valve 107 by means of pump 108. Alkylation reactor 105 is equipped with a mechanical stirrer 109 and a temperature control jacket 110 75

through which may be circulated a suitable cooling or heating fluid by means of lines 111 and 112. The alkylation reaction is carried out at temperatures within the range of 30° F. to 150° F., preferably at about 50° F. and at pressures sufficient to keep the reactants in the liquid phase with contact times within the range of from about five minutes to sixty minutes. The alkylate-acid mixture is transferred to settler 115 by means of pump 114 in valved line 113. In settler 115 the acid separates as a lower layer and it may be recycled through line 116, pump 117, line 118 and line 106 to line 104. Spent sulfuric acid may be withdrawn through valved line 119 to be either concentrated for reuse in the alkylation step or to be diluted for use in the polymerization step described below. The alkylate and unreacted gases are passed via line 120 and pump 121 to a caustic wash step and a water wash step, which steps are not shown in the flow diagram. The washed product is heated in heater 122 and passes by line 123 to fractionator 124 which is equipped with reboiler 125 and reflux producing means 126. Propane and lighter hydrocarbons pass from fractionator 124 through valved line 127 to the fuel burning line. A side stream consisting predominantly of unreacted isobutane and normal butane is withdrawn through valved line 128. This stream may be recycled to the alkylation step feed line 98 via valved lines 128 and 129 or to isomerizer feed line 133 via line 128 for the production of additional isobutane. A second side stream consisting of alkylate having an octane number of 85 to 95 CFR-M and an end point suitable for blending in aviation gasoline or suitable for blending in finished motor fuel is withdrawn through line 130 and passes to line 131 and thence to line 79a for blending with the isomerized C₅+C₆ cut or the alkylate may be sent directly to finished motor fuel line 57 via line 130. Bottom drawoff from fractionator 124 consists of a small amount of alkylate distilling above the gasoline boiling range when operating this fractionator to produce 400° F. end point alkylate drawoff in line 130 for blending with motor fuel. When so operating these bottoms are withdrawn through valved line 130a and accumulated as additional feed to alkylator 105 which may be operated at higher temperatures, for example, from 130° F. to 150° F., as a depolymerization-alkylation reactor to produce a product boiling within the gasoline range when charging such a stock as the bottoms from tower 124 with condensable olefins. When operating to produce an alkylate for blending in aviation gasoline the higher boiling fraction may be further fractionated to produce additional alkylate of 400° F. maximum boiling point for blending in motor fuel and the fraction distilling above 400° F. may be accumulated and used as described above.

As stated above we prefer to isomerize the C₅+C₆ fraction of the virgin naphtha directly to highly branched paraffins for blending in the finished products. On the other hand, it is not desirable to crack this fraction in reactor 28 since the increased yield of non-condensable gases which represent a volume loss of product would be increased and moreover this light fraction is essential in blending to form a balanced aviation gasoline or motor fuel product to furnish desirable volatility characteristics and if isomerized the fraction contributes materially to the anti-knock value of such products. Hence this fraction is drawn off from fractionator 16 through

line 133 by pump 134 along with recycle butane from line 128. A light naphtha fraction containing C₄, C₅ and C₆ paraffins may also be introduced from an external source via line 133a. The mixed hydrocarbon stream is heated in heater 135 which may be a heat exchanger in which the heat is furnished by the product from reactor 28 or reactor 58. Aluminum chloride or aluminum chloride-hydrocarbon complex catalyst, which is activated with hydrogen chloride, is introduced to the hot stream in line 136 via valved line 141 and pump 142. Hydrogen chloride is added to the catalyst in line 141 through valved line 154 and the mixture passes to isomerizer 137 which is equipped with rapid stirring means 138. Reactor 137 may be suitably jacketed and a heating fluid is circulated therethrough by means of valved connecting lines 139 and 140. The isomerization reaction is carried out in the presence of hydrogen or hydrogen mixed with non-condensable gases supplied by the dehydrogenation product via line 67 and compressor 143. Hydrogen may be furnished from an external source through valved line 69 and line 67. We operate isomerization reactor 137 within the range of 250° F. to 400° F., preferably at about 330° F., and at pressures within the range of 200 pounds to 3000 pounds per square inch. The contact time in reactor 137 may be from 5 to 100 minutes.

Part of the catalyst plus isomerized product mixture is withdrawn from reactor 137 by pump 145 through line 144 and passes by line 146 to separator 147 which operates as a catalyst settling zone and also as a release drum in which the hydrogen and hydrogen chloride is separated from the liquid product. The pressure in separator 147 is lowered to the range of 150 pounds to 350 pounds per square inch by opening pressure release valve 153 in line 152 and the mixed hydrogen and hydrogen chloride is recycled via line 154 to catalyst feed line 141 and thence to reactor 137 through pump 142 and line 136. The aluminum chloride catalyst settles from the liquid hydrocarbons in separator 147 from which it is withdrawn by pump 149 in line 148 and it is recycled to reactor 137 through lines 151, 141 and 136. Spent catalyst may be withdrawn from the cycle by means of valved line 150. The hydrocarbon mixture comprising butane, isobutane and the isomerized C₅+C₆ fraction passes via valved line 155 to line 70 which leads to fractionator 12 from which the butanes are recycled to the alkylation step and the isomerized C₅+C₆ fraction of approximately 82 octane number (CFR—M) passes therefrom as blending naphtha to be disposed of as described above. If desired the hydrocarbon stream in line 155 may be subjected to a hydrogen chloride absorbent or neutralizing agent such as solid sodium hydroxide or other neutralizing material in order to remove the last traces of hydrogen chloride before introduction of the stream to line 70.

Referring now to the regeneration of the catalysts in reactors 28 and 58, these may be regenerated by oxidation of the carbonaceous material deposited thereby means of an oxygen containing mixture of gases such as air which may be diluted with flue gas to reduce the oxygen percentage of the gas. Although we have described catalyst chambers as single reactors, these may be provided as multiple units to be operated in parallel banks, either continuously or intermittently, the catalyst in one or more of the chambers of the multiple units being regenerated without interruption of the continuous process. Re-

actors 105 and 137 may also be in multiple. However, the regeneration of the catalyst in reactors 28 and 58 may be accomplished without the use of multiple chambers by a slight change in the mode of operation when it becomes necessary to regenerate either of these catalyst beds. For example, when the catalyst in reactor 28 becomes spent we may isolate reactor 28 by closing valves 27 and 30 and valves 151 and 153 are opened to admit and discharge inert gas from reactor 28 through lines 156 and 158 to remove hydrocarbon vapors. After the reactor is purged the inert gas is gradually enriched with oxygen or air and the carbonaceous material is removed as an oxidation product. The reactor is again purged with inert gas, after which reactor 28 is in condition for use in the hydrocarbon conversion process. During the regeneration of the catalyst in reactor 28 all of the virgin feed may be fractionated in fractionator 66 in order to obtain maximum isobutane in the process. The supply of isobutane for alkylation during this catalyst regeneration period may be augmented by introducing isobutane from an external source via valved line 99 or by introducing normal butane or a normal butane-isobutane stream to butane isomerizer 137 via valved line 128a and lines 128 and 138. As an alternate method of operation during the regeneration of the catalyst in reactor 28 we may operate alkylator 105 as a polymerizer using diluted spent alkylation acid in the hot acid process to polymerize the olefins produced in reactor 58. Reactor 105 is operated at temperatures within the range of 165° F. to 212° F., the acid strength being within the range of 60% to 80% sulfuric acid when polymerizing olefins. The polymer may be separated from the acid in settler 115 and separated from unreacted gases in fractionator 120, polymer of suitable boiling range being withdrawn via line 130 for blending in motor fuel or of suitable boiling range for hydrogenation over suitable catalyst and under conditions well known in the art, the product to be blended in aviation gasoline.

When it becomes necessary to regenerate the catalyst in reactor 58 the reactor may be isolated by closing valves 98 and 69 in lines 92 and 59, respectively, and inert gas and regenerating gas is admitted via valved line 160 to reactor 58 and exits via valved line 162, valves 161 and 163 being open. During the regeneration of the catalyst in reactor 58 reactor 28 may be operated at temperatures within the range of about 800° F. to 850° F. within which temperature range sufficient condensable olefins are produced along with isobutane to alkylate the isobutane in reactor 105. Any make-up hydrogen required for the isomerization reaction in reactor 137 during the regeneration of catalyst bed 58 is furnished from storage via valved line 69, which leads to lines 65 and 67 and thence to reactor 137. During the regeneration of the catalyst in reactor 68 the product from reactor 28 may be sent to fractionator 41, valve 50 in line 49 being closed and a part of the bottoms may be eliminated through valve 58 in line 51, or the product may be sent to line 59 which leads to hydrogen release drum 64 by line 29, valves 42 and 45 in line 29 being open, valve 31 in line 34 and valve 44 in line 43 being closed. With this type of operation recycle from fractionator 12 is directed from line 85 to coil 25 in furnace 24 by closing valve 88 in line 85 and opening valve 87 in line 86, thus com-

bining the recycle bottoms with fresh feed in line 22.

We may also operate reactors 28 and 58 in parallel as well as in series as described above. For example, virgin naphtha of wide boiling range or the C₇ and higher fraction of virgin naphtha may be delivered to lines 22 and 89 from line 21 simultaneously and mixed therein with recycle from fractionators 41 and 72 by lines 55 and 85 respectively, the aromatic bottoms eliminated from each fractionator being discharged to finished product line 57 or the products from reactors 28 and 58 may be sent to a common fractionation system by passing the product from reactor 28 through line 29 to reactor 58 product line 59 via valves 42 and 45, valves 31, 36, 44, 50 and 94 being closed thus providing greater flexibility in the operation of our process to produce the optimum amounts of isobutane and condensable olefins.

By means of our process a typical Mid-Continent straight-run naphtha boiling between 60° F. and 400° F. and having an octane number of 45 to 50 can be converted into high grade motor fuel of 85 to 95 octane number in yields of 80 to 90% on a volume basis. The C₅+C₆ cut of such a naphtha will generally be about 10% to 20% by volume and will have an octane number of 65 to 70. This cut is converted, at least partially, to isobutane in reactor 137, while the residue is isomerized to an octane number of 80 to 85 on a butane-free basis. The volume recovery of this material, including the isobutane, is 95% to 105% by volume.

The C₇ and higher cut of the naphtha generally contains 15 to 25% aromatics having an average octane number of 100, 30 to 40% naphthenes having an average octane number of from 55 to 65 and 40 to 50% paraffins having an average octane number of zero to 15. Under normal operating conditions about 60 to 70% of the paraffins are converted to gases in reactor 28 while 70 to 90% of the remaining paraffins are converted in reactor 58. As previously described these gases are principally C₃ and C₄ hydrocarbons and are converted in reactor 105 to an alkylate of 85 to 95 octane number in yields of 65 to 75% on the basis of the paraffins converted in reactors 28 and 58. The naphthenes are substantially converted to aromatics in reactor 58 so that the liquid product from the bottom of fractionator 72 will be highly aromatic and have an octane number of 90 to 100. As hereinbefore described these high octane number products can be blended together or used separately for special purposes.

We have described a process whereby the low antiknock value of a naphtha may be improved by converting the low antiknock paraffins of said naphtha to valuable condensable gases and by converting the naphthenic components of said naphtha to high antiknock value aromatics. We have also described a unitary process whereby

the condensable gases may be separated from the conversion product and recombined to form naphthas having high antiknock value which can be blended back with the residue naphtha to make motor fuels of greatly increased antiknock value. Although we have described our invention in detail and, therefore, utilized certain specific terms and language herein, it is to be understood that the present disclosure is illustrative rather than restrictive and that changes and modifications may be resorted to without departing from the spirit or the scope of the claims appended hereto.

We claim:

1. The process of producing isobutane which comprises contacting a petroleum naphtha with a solid, silica-alumina cracking catalyst in a reaction zone at a temperature above 575° F. but below 850° F., at a pressure within the approximate range of about 15 to 65 pounds per square inch and at a low space velocity of the order of 0.01 to 1 volume of liquid naphtha per hour per volume of catalyst space in the reaction zone, removing the products from said reaction zone, fractionating the products to obtain a fraction rich in isobutane and a fraction containing hydrocarbons of the naphtha boiling range and recycling at least a substantial part of the last-named fraction to said reaction zone for obtaining further production of isobutane.

2. The process of claim 1 wherein the petroleum naphtha is rich in straight-chain paraffin hydrocarbons and wherein the space velocity is such that from about 5% to about 15% of the straight-chain paraffin hydrocarbons in said naphtha is converted to normally gaseous products per pass through said reaction zone.

3. The process of simultaneously producing isobutane and a motor fuel fraction having a higher antiknock value from a low antiknock naphtha rich in normal paraffin hydrocarbons which process comprises contacting at least a part of said low knock rating naphtha with a solid, silica-alumina cracking catalyst in a reaction zone at a temperature above 575° F. but below 850° F. under an absolute pressure within the approximate range of 15 to 65 pounds per square inch and at such space velocity within the approximate range of about .01 to 1 volume of liquid feed per hour per volume of catalyst space in the reaction zone that the conversion of normal paraffins per pass to normally gaseous products is only about 5% to 15%, fractionating the products to obtain an isobutane fraction and a normally liquid fraction rich in paraffinic hydrocarbons and of higher octane number than the original charge, recycling a substantial portion of the normally liquid fraction to said reaction zone and removing the remainder of said normally liquid fraction.
